UNITED STATES PATENT OFFICE.

CHARLES B. KIRKHAM, OF BUFFALO, NEW YORK, ASSIGNOR TO CURTISS AEROPLANE AND MOTOR CORPORATION, OF BUFFALO, NEW YORK, A CORPORATION OF NEW YORK.

MOTOR-COOLING SYSTEM.

1,294,474.

Specification of Letters Patent. Patented Feb. 18, 1919.

Original application filed September 18, 1915, Serial No. 51,480. Divided and this application filed September 27, 1916. Serial No. 122,439.

To all whom it may concern:

Be it known that I, CHARLES B. KIRKHAM, a citizen of the United States, residing at Buffalo, in the county of Erie and State of New York, have invented certain new and useful Improvements in Motor-Cooling Systems, of which the following is a specification.

This application is a division of my original application Serial No. 51,480, filed Sept. 18th, 1915, on aeronautical motors.

This invention relates to internal combustion engines and has reference more particularly to an improved cooling system designed for use in connection with V-type motors as constructed for high speed service in conjunction with aircraft. Motors of this type must have an ample water circulation to prevent the overheating of the engine cylinders.

Previous cooling systems, in so far as I am aware, operate to force the water or other cooling agent through a single main conduit. From this conduit, branch conduits lead to each cylinder bank and ultimately to each cylinder. The cooling agent travels in but a single main circulatory path. Such an arrangement not only results in retardation of the flow but necessitates the employment of a comparatively powerful pump because of the accumulated skin friction between the cooling agent and the circuit conduits. Moreover, should the flow of the cooling agent be interrupted or retarded at any point, the system in its entirety is immediately impaired.

Absolutely no provision is made for an uninterrupted flow of the cooling agent through one bank of cylinders should the flow in the other bank of cylinders cease.

From the foregoing brief summary, it is apparent that each cylinder bank requires an individual service, *i. e.*—a cooling system dependent upon a pump of duplex characteristics which permits individual service of the cylinder banks without duplication of service pipes, pump elements or similar circuit parts and at the same time permits uninterrupted circulation of water through one bank of cylinders even should the water circulating through the other bank of cylinders be interrupted or stopped.

More specifically, it is proposed by the present invention to provide a pump, the main operating element of which is in the nature of a double impeller so arranged with respect to the pump casing or housing as to independently circulate the cooling agent (in the present instance) via two circulatory paths.

Another and important object of this invention is to so construct and assemble the various pump elements as to provide for a reverse operation of the pump, should the motor be reversed, by simply reversing or re-arranging certain of the various pump elements or parts.

In describing my invention in detail reference will be had to the accompanying drawings wherein like characters of reference designate like or corresponding parts throughout the several views, and in which:

Fig. 1 is a face view of my improved duplex pump illustrating the preferred arrangement of the leads respectively thereto and therefrom;

Fig. 2 is a longitudinal sectional view of the pump and its directly associated driving means;

Fig. 3 is in the nature of a diagrammatic view illustrating the arrangement of the independent circulatory paths of my improved cooling system as arranged upon a multi-cylinder V-type motor;

Fig. 4 is a diagrammatic view similar to Fig. 3 illustrating the arrangement of pump parts reversed;

Fig. 5 is a detail end elevation of the pump casing;

Fig. 6 is a detail sectional view of the inside pump cover plate and its associated integrally formed support;

Fig. 7 is an elevation of the impeller;

Fig. 8 is an inside face view of the cover plate casting illustrated in Fig. 5 and

Fig. 9 is a section on the line 9—9, Fig. 1.

The V-type motor herein diagrammatically illustrated may be generally described as including an upper crank case section and a lower crank case section, cylinders angularly disposed in banks at each side of the longitudinal axis of the crank case, a crank shaft, a cam shaft, and pistons which are adapted to operate in the respec-

tive cylinders in quite the usual manner. Appropriate inlet and exhaust valve operating mechanism may be also included with the elements above noted as essential to the 5 proper operation of the motor. So much of the motor as I have thus generally described may be designated in its entirety by the numeral 10.

The foregoing details or characteristics 10 may be readily changed in any particular manner not conflicting with the application of this invention thereto since it is the purpose of the invention to adapt an explosion engine having these general characteristics 15 to the high speed demands of aeronautical work by providing an adequate water cooling system. This system generally contemplates the individual service of the opposed cylinder banks and secures such service from 20 a single pump duplex in form.

The pump casing 11 is of the general shape best illustrated in Fig. 2, including a hollow body and a pair of inlet tubes 12 communicating therewith. Within the pump 25 body is rotatably mounted an impeller 13 comprising a disk 14 having its lateral faces formed with curved radially staggered vanes 15. The body of the pump is of a construction affording a pair of pump chambers 30 adapted to be partially separated by an interiorly located annular flange 16 and to be completely separated by the impeller disk 14, the disk acting in conjunction with the flange to prevent communication be- 35 tween the chambers even during rotation of the impeller. With each of these chambers there connects one of the inlets 12 as well as outlets 17. The outlets extend laterally part way around the pump casing to a point on a line tangentially thereto or as illustrated to 40 advantage in Fig. 1. A two-way or double elbow 17' is located at the adjacent outlet terminals to engage with the opposed or oppositely extending feed-conduits later to 45 be described.

Each of the cylinders of the engine is provided with a water jacket which is spaced from its cylinder in any desirable manner, completely inclosing the explosion chamber 50 thereof. The lowest point in each water jacket is connected directly to a manifold 18 serving the bank to which the cylinder belongs, such manifold connecting, obviously, to one of the pump outlets 17. Oppositely 55 extending conduits 19 afford the connecting means. From the highest point of each jacket, and diametrically opposite, a branch pipe leads, the pipes collectively serving to return the cooling agent, via the manifold 60 20, the radiator (not shown) and a return conduit 21, to the pump casing where it is again and continuously circulated in the paths thus defined.

The impeller 13 is keyed upon a shaft 22 65 and adapted to be actuated through the

medium of a gear 23 mounted on this shaft to intermesh with a crank shaft gear (undisclosed) which is the lowermost element of a train of gears located at the forward or front end of the motor. While this drive 70 arrangement is probably the most compact that could be constructed for the manifold requirements, it will be apparent that any desirable drive means for the pump can be used.

More specifically, the pump casing 11 may be described as comprising a body member 24 and cover plates 25 and 26, the plates engaging with the body member 24 after the manner illustrated in Fig. 2. The inside 80 cover plate 26 has an integrally cast shell 27 formed thereon. The shell or support, as it may be more properly termed, is of a size and shape in cross section to completely embrace the pump shaft 22 and a packing gland 85 28 mounted adjacent the outer end of the said shaft at a point where the shaft penetrates the inner pump casing cover plate 26. In fact, the shell or support 27 is cut away as indicated at 29 that access may be gained 90 to the packing gland 28 when required.

Ears 30, preferably three in number, are formed upon the support 27 to engage with the end crank case cover of the motor, designated 31. Bolts 32 are utilized to penetrate 95 the ears 30 and the crank case cover 31 to afford a positive fastening means for the support and the pump casing carried thereby. This construction will eliminate the use of unnecessarily long bolts and yet provide for proper spacing of the pump away from the crank case cover. It is essential that the pump be thus spaced in order that the inlet 12 located at the inner side of the pump may extend therefrom after the 100 fashion disclosed. Bearings of an appropriate design engage with the shaft 22.

By reference to the diagrammatic view Fig. 4, it will be noted that the conduit 19 and the double-elbow 17' have been reversed. This reversible feature is, I believe, essentially novel. Without the introduction of a single new element and by simply re-arranging certain of the component pump parts the 110 operation of the pump may be quickly and 115 completely reversed. In obtaining a reverse operation of the pump it is but necessary to remove and replace the cover plate 25, remove, reverse and replace the conduits 19 and the elbow 17' and remove, reverse and 120 replace the pump body 24 and the impeller 13. This re-arrangement of parts, (assuming, of course, that the motor has been reversed) will, without alteration, completely 125 and effectually reverse the operation of the pump. It is to secure this essential feature that the front cover 25 and the body 24 are made separate. Were the motor reversed and the pump parts unchanged as regards arrangement, the cooling agent, while active 130

in so far as circulation is concerned, would circulate in a direction exactly opposite to that required. The parts enumerated only need be reversed.

5 In practice, the cooling agent is indrawn at opposite sides of the impeller disk into the pump casing and expelled therefrom by the action of the impeller. From the pump casing, the cooling agent travels in a circulatory path through the conduits 19, the manifolds 18, the cylinder water jackets, the manifolds 20, the radiator and the conduits 21 in the order named, the conduits 21 returning the cooling agent again to the pump casing for continued circulation after the manner disclosed. By dividing the pump casing interiorly, two independent yet correlated circuits are in evidence. The circuits in a sense act conjointly by reason of the 20 utilization of but a single pump structure yet actually operate independently in that the cooling agent circulated for cooling each bank of cylinders travels in a distinct and non-communicating path. As suggested, 25 should the water flow of one circuit be interrupted or checked, the water flow in the other circuit will be in no wise affected. Even should the impeller at one side of the disk 14 be impaired, the circulation occasioned by continued rotation of the remaining active portion of the propeller would 30 continue.

The advantages of a cooling system such as that described are believed to be evident 35 from the fact that each cylinder bank is given a better service and a more direct service, while at the same time the number of pumps is not increased owing to the fact that the pump casing is provided with a 40 similar pair each of inlets and outlets which respectively communicate with the opposed chambers, the inlets centrally of the pump casing and at opposite sides thereof and the outlets laterally of the pump casing and in 45 a sense circumferentially or tangentially thereof. The location of the outlets with respect to the pump casing is such as to enable the pump to centrifugally expel the water via the conduits 19. To drain the 50 pump casing a single plug 33 is provided, the plug engaging at the lower end of the pump casing with the flange 16, the said flange affording an abutment whereby adjustment of the plug is limited. By removing 55 the plug both sections or chambers of the pump casing may be effectually drained.

Although I have described more or less precise forms and details of structure, I do not intend to be understood as limiting myself thereto as I contemplate changes in form, the proportion of parts and the substitution of equivalents as circumstances may suggest or render expedient and without departing from the spirit of the invention as claimed.

What is claimed is:

1. The combination with an internal combustion engine having cylinders arranged in banks, of a cooling system including a multiple pump having an element individual to 70 each of said banks and a cooling circuit for each of said cylinder banks establishing communication therebetween and the corresponding pump element.

2. The combination with an internal combustion engine having cylinders arranged in banks, of a cooling system including a pump having a separate element individual to each of said banks, a circuit for each bank separately connecting with its pump supply 80 element, and a means coöperating with said pump for partitioning the correlated circuits to permit of the independent circulation of a cooling agent therethrough.

3. The combination with an internal combustion engine having cylinders arranged in two banks, of a cooling system including a duplex pump, circuits separately connecting with the members of said duplex pump for independent service of each cylinder bank, 90 and a means mounted within the pump and coöperating therewith to separate the circuits and simultaneously force a cooling agent therethrough.

4. The combination with an internal combustion engine having cylinders arranged in two banks, of a cooling system including an independent circuit for each of said cylinder banks, and a duplex pump dually functioning to separate the correlated circuits and to 100 force a cooling agent therethrough, each of the elements of the duplex pump together with the corresponding cooling circuit serving as an independent cooling system for 105 each bank of cylinders.

5. The combination with an internal combustion engine having cylinders arranged in banks, of a cooling system including an independent circuit for each of said cylinder banks, a means partitioning the circuits to 110 permit of unrestricted circulation through one in the event of an interrupted circulation through the other, and a means common to both circuits for simultaneously inducing independent circulation therein.

6. The combination with an internal combustion engine having cylinders arranged in banks, of a cooling system including a pump, circuits separately connecting with said pump, and an impeller mounted within the pump to separate the circuits and simultaneously force a cooling agent therethrough.

7. The combination with an internal combustion engine having cylinders arranged in 115 banks, of a cooling system including a pump having a central body, an impeller mounted within said body to subdivide the same into chambers, vanes carried by said impeller for projection into each chamber, and separate 120

circuits for the service of said cylinder banks, such circuits independently connecting the respective chambers.

8. The combination with an internal combustion engine having two fluid circulating circuits, of a pump having a central body, an impeller rotatably mounted within said body and subdividing the same into chambers, vanes arranged on both faces of the 10 propeller to project into opposite chambers, separable circuits connecting with respective chambers and with said circulating circuits, and inlets also communicating with the pump body through respective chambers.

9. The combination with an internal combustion engine, of a cooling system including a pump, an impeller mounted within the pump and having its lateral faces disposed 20 toward separate portions of the pump, circuits arranged to connect independently to the pump by entrance thereinto adjacent opposite impeller faces, and inlets for the pump also connecting thereto adjacent opposite impeller faces.

10. The combination with an internal combustion engine of a cooling system including a water pump reversible by re-arrangement of certain of the pump parts to 30 secure proper circulation of the cooling agent should the engine be reversed.

11. The combination with an internal combustion engine of a water pump including a reversible impeller, an impeller shaft, 35 and a reversible pump body having reversible conduits leading therefrom to secure a complete reverse operation of the pump without altering the circulatory path of the cooling agent forced therethrough and with-

out alteration but rearrangement of the 40 pump parts.

12. The combination with an internal combustion engine, of a cooling system including a pump having reversible conduits leading therefrom, and an impeller reversible with respect to its support to secure a reverse operation of the pump.

13. The combination with an internal combustion engine and water cooling jackets of a water circulating pump including a reversible impeller, an impeller shaft, a symmetrically arranged cylindrical pump casing inclosing said impeller and having a tangential outlet, a pair of end closing plates adapted to receive said cylindrical 55 casing therebetween and having their engaging surfaces complementally and similarly formed to receive said cylindrical casing in either of its reversed positions, and connections leading from said tangential 60 outlet to said water jackets whereby complete reversal in operation of the pump may be effected without altering the circulatory path of the cooling agent forced therethrough and without alteration but rearrangement of the pump parts.

14. In an engine motive power apparatus, the combination of a plurality of cylinders arranged in sets having jackets for the circulation therethrough of a cooling fluid, of 70 a cooling system including a multiple pump having elements individual to said sets of cylinders, and cooling circuits individual to said sets of cylinders for establishing communication therebetween and the corresponding pump elements.

In testimony whereof I affix my signature.
CHARLES B. KIRKHAM.
